Primary Examiner — Amy C Wierenga*Assistant Examiner* — Kathryn Elizabeth Zieno(74) *Attorney, Agent, or Firm* — Tutunjian & Bitetto, P.C.(57) **CLAIM**

The ornamental design for a flow corrector, as shown and described.

DESCRIPTION

FIG. 1 is a perspective view of a flow corrector showing our new design;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a rear view thereof.

The dashed lines in the drawings depict portions of the flow corrector that form no part of the claim.
